ABRAHAM HOYT LEVY, OF NEW YORK, N. Y., ASSIGNOR TO SYRACUSE SMELTING WORKS, OF BROOKLYN, NEW YORK, A CORPORATION OF NEW YORK.

METAL-CLEANING APPARATUS.

1,298,229.

Specification of Letters Patent. Patented Mar. 25, 1919.

Continuation of application Serial No. 89,742, filed April 8, 1916. This application filed November 10, 1917. Serial No. 201,222.

To all whom it may concern:

Be it known that I, ABRAHAM HOYT LEVY, a citizen of the United States of America, residing at the borough of Bronx, in the city of New York, county of Bronx, and State of New York, have invented certain new and useful Improvements in Metal-Cleaning Apparatus, of which the following is a specification, reference being had to

10 the accompanying drawings.

This invention relates to improvements in metal-cleaning apparatus, and particularly to improvements in metal-cleaning apparatus using a flux, although not restricted 15 to such apparatus; and an object of this invention is to provide a metal-cleaning apparatus which will be simple in construction, comparatively cheap in manufacture, and efficient and labor-saving in operation 20 and use.

In the drawings illustrating the principle of this invention and the best mode now known to me of applying that principle, Figure 1 is a front elevation of the furnace 25 with the metal-cleaning apparatus in place; Fig. 2 is a fragmentary central vertical section on the line 2—2 of Fig. 1 and through the melting pot, and shows the cleaning apparatus fastened in operative position; Fig. 30 3 is a plan of the cleaning apparatus detached from the furnace; Fig. 4 is a detail showing the shell in vertical central section; Fig. 5 is a perspective view illustrating a modified form of cleaning apparatus in place 35 in the melting pot of a furnace, parts being broken away to permit of clearness of illustration; Fig. 6 is a plan of the cleaning apparatus shown in Fig. 5; and Fig. 7 is an elevation of a second modified form of the 40 cleaning apparatus.

The furnace *a* is provided with a firepot door *b* and with a pair of doors *c* which close the opening *d* to the melting-pot *e*. In the latter, the metal *f* (such as type 45 metal) to be cleaned is subjected to heat, until the metal is in a molten condition. The cleaning apparatus consists of a handle-bar *g* formed, at its outer end, with a crosspiece *h* that serves as a handhold and,

at its inner end, with a tubular guide-member *i*, in which there is slidably fitted a vertically-disposed rod *j* the lower end of which is fastened to the hinged cover *k* of a shell *m* formed with perforations *o*. The cover *k* is hinged at *p* to the shell *m*, 50 which is formed with an ear *q*, with which is engaged the hasp *r*, whereby the cover *k* is held locked down in place on the shell *m*. A gas-liberating flux *s* is held in a container *t* made of perishable material (such as 55 pasteboard or the like) and shaped like a cartridge and having its lower end *t'* pointed (or conical) in shape and its top *t''* formed with an annular flange *t''*. The conical end *t'* of the container *t* fits snugly into 60 the conical lower end *m'* of the shell *m*; and the flange *t''* of the container *t* serves to hold the cylindrical wall *t''* spaced from the cylindrical wall *m''* of the shell *m*. By means of a set screw *u*, the rod *j* is held 65 in its adjusted position. Upon the bottom edge *d'* of the opening *d*, there is mounted a clamp *v*, the outer end of the body *v'* of which is formed with an ear *v''*, through a 70 threaded opening in which there is passed a clamp-screw *w* having at its outer end a handwheel *w'*. The inner end of the body *v'* of the clamp *v* is bifurcated and each branch or fork *v''* is formed with a lip *v''*, 75 between which and the inner end of the clamp-screw *w*, there passes the bottom edge portion *d'* of the opening *d*. By means of a 80 set screw *x*, the handle-bar *g* is held in its adjusted position in the clamp *v*.

The operation of the cleaning apparatus 85 hereinbefore described is as follows: A gas-liberating flux is placed in the pasteboard, cartridge-shaped box *t*, which is then inserted in the shell *m*, whereupon the cover *k* of the latter is closed and, by means of the hasp *r*, is locked down upon the shell *m*. The position of this shell *m* may be adjusted vertically by loosening the set screw *u* and slipping the rod *j* up or down in the guide *i*, as may be desired; and, after the 90 vertical adjustment has been made, the set screw *u* is tightened. The clamp *v* is fastened to the edge portion *d'* of the wall of

the melting-pot *e* by tightening the screw *w*; and the handle-bar *g* is inserted in the clamp *v* and, after having been adjusted horizontally to its proper position, the set screw *x* is tightened. The molten type-metal enters the foraminated shell *m* through the perforations *o* formed therein and the pasteboard box *t* is thus destroyed, whereupon the flux *s* flows out through the holes *o* and mixes with the molten type-metal *f*. The mixing of the gas-liberating flux *o* with the latter causes an agitation of the molten metal by the liberation of gases, as well as serves to clean the same. This agitation serves to obviate the necessity of stirring the metal *f*, while it is being melted. Moreover, this cleaning apparatus does away with the necessity of a workman's holding down the shell *m*; and, since the apparatus may be adjusted both horizontally and vertically, the shell *m* may be quickly put in the melting-pot *e* in any position desired without having to exercise great care with regard thereto; and the apparatus may be readily fitted to melting pots of different sizes and capacities. The buoyant effort of the molten metal *f* is considerable and taxed greatly the strength of the workman who was, in the methods heretofore employed, charged with the duty of holding the flux-container in the liquid metal. By means of the structure hereinbefore described, the buoyant effort is resisted mechanically.

Cases arise in which the bottom edge portion of the opening *d* is not well adapted for use with the clamp *v*; and, for such cases, I have provided the form of apparatus illustrated in Figs. 5 and 6. In this form, the clamp *v* is entirely omitted and the handle *g'* is simply laid upon the bottom edge *d'* of the opening *d*. To the inner end of the handle *g'*, there is fastened an L-shaped bracket *y*, the vertical part *y'* of which supports the outer ends of a pair of bars *z*, the inner ends of which are formed with guides *i*, through which are slipped the rods *j* that carry, at their lower ends, the shells *m* and that are fastened in their adjusted position by means of the set screws *u*. On each of the bars *z*, between the vertical part *y'* of the bracket *y* and the guide *i*, there is slidably mounted a block of metal *2* the weight of which resists the upward thrust due to the buoyant effort of the molten metal *f*. By shifting the position of the metal blocks *2*, this buoyant effort may be nicely balanced. By turning the vertical part *y'* of the bracket *y* upward, the weights *2* are held above the level of the metal *f*, in case the melting-pot *e* becomes well-filled. The cleaning apparatus may be compactly arranged for storage, when not in use, as is illustrated in Fig. 6 in dotted lines. The set screws *u* are loosened, the rods *j* are withdrawn from the

guides *i* and are passed through holes 3 in 65 the bracket member *y'* into sockets 4 formed in the outer faces of the weights *2*. A retainer 5 is passed around the rods *j* near the shells *m*. Less or more than two weights *2* may be used depending on the nature of the 70 molten metal and the size of the melting used, pots for linotype metal being small and those for stereotype metal being larger and requiring two or more weights *2* to be used. 75

Another means of overcoming the buoyant effort of the molten metal mechanically consists in utilizing for this purpose the weight of a standard similar to that used by the police of large cities for the purpose of regulating street traffic. This device is illustrated in Fig. 7, wherein the outer end of the horizontally-disposed, shell-supporting bar *g''* is bent vertically downward to form a leg *g'''* which enters slidably the socket in 85 the standard or post *6* that rises, pedestal-like, from the base *7*. By means of a set-screw *8*, the leg *g'''* is secured in adjusted position; and the buoyant effort of the molten metal is effectually resisted by the weight of 90 the post *6* and its base *7*.

This application is filed as a continuation of my allowed application, Serial No. 89742, filed April 8, 1916.

I claim:

1. A metal-cleaning apparatus including a receptacle; a rod to which said receptacle is attached; a handle-bar in which said rod is mounted and which is angularly disposed thereto; and means for maintaining said 100 handle-bar against the thrust due to the buoyant effort of the molten metal in which said receptacle is held.

2. A metal-cleaning apparatus including a receptacle; a rod to which said receptacle is 105 attached; a handle-bar in which said rod is mounted and which is angularly disposed thereto; and a weight for counter-balancing the thrust due to the buoyant effort of the molten metal in which said receptacle is 110 held, said weight being adjustable to vary its counterbalancing effect.

3. A metal-cleaning apparatus including a receptacle; a rod to which said receptacle is attached; a handle-bar in which said rod is 115 mounted and which is angularly disposed thereto; and a weight for counter-balancing the thrust due to the buoyant effort of the molten metal in which said receptacle is held; said handle-bar being formed with 120 a raised portion by means of which the weight is kept at all times above the level of the molten metal.

4. A metal-cleaning apparatus including a receptacle; a rod to which said receptacle is 125 attached; a handle-bar in which said rod is mounted and which is angularly disposed thereto; and a weight for counterbalancing

the thrust due to the buoyant effort of the molten metal in which said receptacle is held, said weight being formed with an opening to receive an end of said rod, when 5 said apparatus is dismantled.

Signed at the borough of Brooklyn, city of New York, county of Kings and State of

New York, this ninth day of November, 1917, in the presence of the two undersigned witnesses.

A. HOYT LEVY.
